UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

ARC-LAMP.

1,190,159.

Specification of Letters Patent.

Patented July 4, 1916.

Application filed September 16, 1914. Serial No. 861,961.

To all whom it may concern:

Be it known that I, CROMWELL A. B. HALVORSON, Jr., a citizen of the United States, residing at Lynn, county of Essex, State of Massachusetts, have invented certain new and useful Improvements in Arc-Lamps, of which the following is a specification.

My invention has reference to arc lamps mounted on posts or other supports, and is particularly applicable to inclosed flame arc lamps although not limited to arc lamps of this character.

Inclosed flame arc lamps have hitherto been built comprising a substantially air tight arc inclosure formed of an inclosing globe open at the top and seated against and communicating with a superimposed depositing chamber within which the gases evolved from the arc circulate and where the solidifiable products of combustion are deposited. Lamps of this character are usually provided with an outer globe to keep the inner globe hot and to improve the distribution of light. When such lamps are suspended in the usual way, it is only necessary to either lower or remove the globes in order to trim the lamp and clean the globe. When, however, the lamp is mounted upon a post or other support, special provision must be made for obtaining access to the inner globe for the purpose of cleaning the same and of trimming the lamp, and the provision of means for this purpose is one of the objects of my invention.

A further object of my invention is the provision of a novel form of outer globe and support therefor.

Other objects of my invention will be apparent from the description and will be particularly pointed out in the claims.

For a fuller understanding of my invention reference may be had to the accompanying drawings in which—

Figure 1 is a side view of a lamp embodying my invention with certain portions in section and with some portions broken away; Fig. 2 is a sectional plan view partially broken away, showing the door formed in the outer globe in open position; Fig. 3 is a sectional elevation of a part of the lamp; Fig. 4 is a fragmentary plan view showing a portion of the upper ring of the globe cut away to form a seat for the door in which is mounted a panel of the outer globe; and Fig. 5 is a detail sectional view on the line 5—5 Fig. 1, showing a locking device for

the door in the outer globe at the bottom thereof.

Referring now to the drawings in which like reference characters indicate the same parts in the different views, 10 is a post or other support upon which is mounted a supporting frame for the outer globe and for the lamp itself. This frame comprises a lower annular ring 11 mounted upon the support 10 and an upper ring 12 which is joined with the ring 11 by suitably formed ribs 13, 14, 15 and 16, each in a vertical plane with the axis of the rings 11 and 12. The ribs 13 and 16 are longitudinally divided into sections 13^a and 13^b, and 16^a and 16^b respectively. (See Fig. 2.) The rib sections 13^b and 16^a are fixed members of the globe frame while the rib sections 13^a and 16^b form with the ring sections 11^a and 12^a a door frame 17 which is hinged at 18 to section 16^a of the rib 16. The bottom ring 11 is provided with a slot 20 (see Fig. 5) beneath the door 17 for the reception of a lug or pin 21 carried by the ring section 11^a for the purpose of locking the door in its closed position. The section 11^a is provided with an outstanding lug 22 in which is secured a ring 23 by which the door may be lifted and opened.

The outer globe A is composed of a number of panels 24, 25, 26 and 27, three of which, 24, 25 and 26, are seated against the flanges 28 formed at the inner edges of the ribs 13, 14, 15 and 16, as shown in Fig. 2, and against ledges 29 formed on the upper ring 12, as shown in Fig. 3, and on the lower ring, as shown in Figs. 1 and 5, the panel 27 being mounted in the door frame 17. The various panels are preferably held in position by flexible means which I have here shown as coil springs 30 which are secured at their ends to adjacent ribs, the ends of the springs which hold the panel of the door in position being secured to the rib sections of the door frame. The springs engage the panels at the top and bottom respectively, the top and bottom edges of the panels preferably being curved outwardly so that a seat for the springs against the panels is provided.

The arc lamp frame B is mounted on the top of the supporting frame. I have here illustrated my invention in connection with an inclosed flame lamp of the type in which an inner globe open at the top is seated against and communicates with a superim-

posed depositing chamber into which the gases evolved from the arc ascend and in which solidifiable products of combustion are deposited. This depositing chamber, which for convenience I have referred to as a part of the arc lamp frame is represented by the numeral 31. This depositing chamber is of a diameter rather large in proportion to its height and is preferably formed to extend laterally well beyond the top of the supporting frame. The under side of the depositing chamber is preferably provided with a downwardly extending flange 31^a against which is seated, substantially air tight, the inner globe 32. The inner globe and depositing chamber thus form a substantially air tight inclosure. The bottom plate 33 of the lamp frame, which I have here shown in the form of a frustum of a cone, is received in an opening 34 in the top wall of the depositing chamber. The upper electrode 35 passes through the bottom plate 33 in the usual way; while the lower electrode 36 is carried by a rod 37. A tube 40 for the accommodation of the conductors leading from the support 10 to the arc lamp mechanism passes through the upper and lower walls of the depositing chamber.

It will be understood, of course, that any desired feeding mechanism may be used for the lamp, although with a structure such as I have here shown, it will usually be preferable to employ a focusing mechanism, the mechanism for the lamp being carried by the arc lamp frame above the depositing chamber and inclosed within a casing which will preferably be formed to harmonize with the appearance of the outer globe.

In order to readily bring the inner globe into the opening formed by the door in the outer globe when the door is open, the depositing chamber is hinged to the upper ring 12 at 38 at a point opposite the door in the globe. The lower side of the depositing chamber is provided with a flange 39 which engages, on its inner face, the upper ring 12 so that when the depositing chamber is in position it will lock the ring section 12, including the section 12^a and thereby the door in position.

The inner globe and the door in the outer globe are of such relative sizes that the inner globe may readily be removed through the opening formed by the door when the same is open. Now, in order to trim the lamp it is only necessary to first slightly tilt the lamp about the hinge 38, which unlocks the door, then open the door and then further tilt the arc lamp frame about the hinge 38 which brings the inner globe into the opening in the outer globe. The inner globe then may readily be removed.

In accordance with the provisions of the patent statutes, I have described the principle of operation of my invention, together

with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In an arc lamp, a supporting frame, a globe secured to said frame and provided with a removable panel, an arc lamp frame mounted upon said supporting frame, an inner globe secured to said frame and depending within the outer globe, the arc lamp frame being tiltably mounted on the supporting frame so as to bring the inner globe opposite the removable panel when the arc lamp frame is tilted.

2. In an arc lamp, a supporting frame comprising a number of substantially vertical ribs, an outer globe divided into a number of panels secured between said ribs, one of the panels being pivotally mounted whereby the same may be opened, an arc lamp frame mounted upon said supporting frame, and an inner globe secured to said arc lamp frame and depending within the outer globe, the arc lamp frame being pivoted opposite the pivoted panel whereby the inner globe is brought into the opening formed by said panel when the arc lamp is tilted.

3. In an arc lamp, a supporting frame, an outer globe secured to said frame and provided with a removable panel, an arc lamp frame provided with a depositing chamber for fumes evolved from the arc mounted upon said supporting frame, an inner globe open at the top secured beneath the depositing chamber and communicating therewith, said depositing chamber being pivoted to said supporting frame opposite the removable panel, whereby the inner globe is brought into the opening formed by the removable panel when the arc lamp frame is tilted.

4. In an arc lamp, a supporting frame comprising upper and lower rings joined by a number of ribs, an outer globe divided into a number of panels mounted between said ribs, one of the panels being mounted on a hinged frame, an arc lamp frame mounted upon the top ring of said frame and hinged thereto opposite the removable panel, an inner globe secured to the arc lamp frame and depending within the outer globe, whereby when the arc lamp is tilted the inner globe is brought into the opening formed by the removable panel.

5. In an arc lamp, a base, a supporting frame mounted thereon, an outer globe secured thereto, an arc lamp frame comprising a flat depositing chamber seated upon said supporting frame, an inner globe secured against said depositing chamber, and

a tube extending through the upper and lower walls of the depositing chamber and communicating with the space between the inner and outer globes for accommodating the conductors extending from the base to the arc lamp.

5 In witness whereof, I have hereunto set

my hand this eleventh day of September 1914.
